US0D1045803S

(12) **United States Design Patent** (10) Patent No.: **US D1,045,803 S**
(45) Date of Patent: ** Oct. 8, 2024

(54) **CHARGING ADAPTER**

(71) Applicant: **SHENZHEN YONGCHUANGCHENG TECHNOLOGY CO., LTD.**, Shenzhen (CN)

(72) Inventor: **Lijuan Yang**, Shenzhen (CN)

(73) Assignee: **SHENZHEN YONGCHUANGCHENG TECHNOLOGY CO., LTD.**, Shenzhen (CN)

(**) Term: **15 Years**

(21) Appl. No.: **29/877,116**

(22) Filed: **Jun. 1, 2023**

(51) LOC (14) Cl. **13-03**

(52) U.S. Cl.

CLAIM

The ornamental design for a charging adapter, as shown and described.

DESCRIPTION

FIG. 1 is a perspective view of a charging adapter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the charging adapter that form no part of the claimed design.

1 Claim, 8 Drawing Sheets
